ATTORNEY.

UNITED STATES PATENT OFFICE.

WILLIAM J. STEWART, OF WILLIAMSPORT, PENNSYLVANIA, ASSIGNOR OF THREE-FOURTHS TO ISAAC C. SMITH, JOSEPH KUNKEL, AND JONAS PARKER, ALL OF SAME PLACE.

SUSPENDERS.

SPECIFICATION forming part of Letters Patent No. 449,141, dated March 31, 1891.

Application filed November 1, 1890. Serial No. 370,031. (No model.)

To all whom it may concern:

Be it known that I, WILLIAM J. STEWART, a citizen of the United States, residing at Williamsport, in the county of Lycoming and

5 State of Pennsylvania, have invented certain new and useful Improvements in Suspenders; and I hereby declare the following to be a full, clear, and exact description of the same, reference being had to the accompanying drawings, wherein—

10 Figure 1 is a perspective view of portions of a suspender illustrating my invention. Fig. 2 is a longitudinal section of the same on the line $\alpha\alpha$, Fig. 1. Fig. 3 is a detached view 15 of the end of the suspender-web and its ring. Fig. 4 is a detached view of the triangle used with a continuous-web suspender, and Fig. 5 is a detached view of a buckle having a hook to engage the end ring of the web.

20 Like symbols refer to like parts wherever they occur.

My invention relates to the construction of attachments for suspenders, whereby simple and effective means for adjusting the length 25 of the suspenders and for securing and releasing the tabs or tugs are obtained.

It consists, generally stated, in the combination, with a suspender-end, of a folded metal clamping-plate, a ring secured thereby 30 to the end of the web, a slide or buckle arranged on the web and having a hook, with which the end ring engages, and tugs having a web-loop, through which the web of the suspenders passes, all substantially as will hereinafter more fully appear.

For purposes of illustration a continuous-web suspender has been chosen, but the invention is not to be limited thereto, as several of the attachments are equally applicable to 40 other common forms of suspenders.

I will now proceed to describe my invention more fully, so that others skilled in the art to which it appertains may apply the same.

In the drawings, A indicates portions of a 45 suspender-web, which, if a continuous-web suspenders, may be folded upon and passed through a triangle B, said triangle having the usual tug-spool b and tug b' or any equivalent finish.

50 The free ends of the web A are each pro-

vided with a folded metal plate and finish or clamp 1, having an end ring or loop 2, adapted to engage with a suitable hook or its equivalent.

3 indicates an adjustable buckle or clamp-slide provided with a hook 4 or like means of engaging the end ring 2 of the web. Two adjustable buckles or clamp-slides are necessary, one for each shoulder-strap, and are preferably of the general form shown in Fig. 55 60—that is, a buckle-frame provided with raised-bed bars c , a pivoted slotted presser-plate d , and having a pivoted hook 4, pivoted on the presser-plate and adapted to pass under the lower bar of the frame c and engage the 65 end ring 2 of the web A.

5 indicates a web-loop, to which is attached a tug-spool b^2 or other suitable means for securing the tug b^3 .

The end ring 2 and clamp-slide provided 70 with hook 4 may be used with the usual forms of suspenders; or by the use of all the attachments the suspenders may be formed from a continuous piece of webbing. In the former case the end rings 2 will be attached to the 75 free ends of the shoulder-straps, with the fold of the metal to the front, as shown in Fig. 3. The buckle or clamp-slide 3 will then be placed on the shoulder-strap and the end of the shoulder-strap passed from the back through the 80 web-loop 5 of the tugs and turned upon the front until the end ring 2 engages the hook 4, when the shoulder-strap is lengthened or shortened by adjusting the buckle or clamp-slide down or up on the web A. In the latter 85 case or where a continuous web is used the end rings 2 are attached, as before, to the opposite ends of the web A, the fold of the metal to the front in case of both end rings. The web A is then folded at its center on the triangle B and passed therethrough, (see Fig. 1;) the clamp-slides 3 placed on the web on opposite sides of the triangle B; the ends of the web passed through the web-loops of the tugs from back to front, and the end rings caused 95 to engage the hooks of the clamp-slides 3, after which the clamp-slides or buckles may be adjusted as before to obtain the required length of shoulder-straps.

Among the advantages of my invention are 100

the facility with which the tugs may be detached from the shoulder-straps, (or web A,) the support and finish secured for the free ends of the suspender-webbing, the ready adjustability of the suspenders, and the neat and finished appearance of the article.

- Having thus described my invention, what I claim, and desire to secure by Letters Patent, is—
- 10 1. The combination, with a suspender-web, of a folded metal-plate clamp, a hook-ring secured to the end of the web by said clamp, a slide or buckle arranged on the web and having a hook for engaging said ring, and suspender-tugs having a web-loop, through which
  - 15

the web of the suspenders passes, substantially as and for the purposes specified.

2. The combination, with a suspender-web, of a loop or ring end, a clamp-slide having a hook, with which the loop or ring end engages, ²⁰ and a tug having a web-loop for the passage of the suspender-web, substantially as and for the purposes specified.

In testimony whereof I affix my signature in presence of two witnesses this 31st day of ²⁵ October, 1890.

WILLIAM J. STEWART.
